GAS CONTROL MECHANISM

Frank S. Summer, Long Beach, N. Y.

Application June 6, 1930, Serial No. 459,605
Renewed July 27, 1934

9 Claims. (Cl. 158—117.2)

In the preferred form of the mechanism it is used in connection with a gas burner such as is ordinarily associated with a gas range, it being understood, however, that the invention is not 5 to be so limited. It may be used in other obvious manners readily apparent to one experienced in the art.

The object of my invention is to produce a device which is automatically operative to prevent 10 a flow of gas to the burner if for any reason the gas flame is accidentally extinguished. Other objects are to construct a device which appears similar to and is actuated in substantially the same manner as the ordinary gas valve and also 15 to provide a mechanism in which the parts are so associated as to assure a positive operation of the same during the lifetime of the valve.

In carrying out the invention I prefer to utilize 20 a control valve, the movement of which is actuated by the expansion of a thermostatic device which receives its heat from the flame of the burner. Associated with the control valve is a main valve which regulates and permits the adjustment of the flame when the control valve has 25 been opened. An auxiliary valve is utilized to establish an initial flow of gas to the burner whereby the ignition of the same generates sufficient heat to cause the expansion of the thermostatic device and thereby open the control 30 valve. The expansion of the thermostatic device simultaneously facilitates the opening of the control valve thereby establishing the flow of gas through the main valve to the burner and also closes the auxiliary valve. If for any reason the 35 flame is accidentally extinguished at the burner the contraction of the thermostatic device permits the closing of the control valve and in this manner the flow of gas through the main valve is terminated. Inasmuch as the auxiliary valve 40 has heretofore been closed, it is obvious that the flow of gas to the burner is automatically terminated substantially simultaneously with the extinguishing of the flame.

In the accompanying drawings:

Figure 1 is a sectional plan of the mechanism.

Fig. 2 is a sectional elevation showing the arrangement of the mechanism with the gas burner.

Fig. 3 is an elevation illustrating the body portion of the main and auxiliary valves.

Fig. 4 is a diagrammatic view showing the position of the valves when the operating lever is turned off.

Fig. 5 is a diagrammatic view illustrating the

valves when the lever is turned in the on position in starting the mechanism.

Fig. 6 is a diagrammatic view illustrating the position of the valves under normal operating conditions.

Fig. 7 is a diagrammatic view showing the position of the valves if the flame is accidentally extinguished.

Fig. 8 is a sectional elevation and a modification of my invention.

Fig. 9 is a plan of the device as illustrated in Fig. 8.

Fig. 10 is a section on line 10—10, Fig. 8.

Fig. 11 is a sectional elevation showing the positions of the valves when the operating levers 15 are actuated to start the device.

Fig. 12 is a sectional elevation showing the positions of the valves under normal operating conditions, and

Fig. 13 is a sectional elevation illustrating the 20 positions of the valves if the flame is accidentally extinguished.

Referring to Figures 1 and 2 an embodiment of my invention is incorporated within a casing 20. One end of the casing 20 is screw threaded 25 as indicated at 21 to form a connecting means to a gas supply main 21'. The opposite end of the casing 20 comprises a circular wall 22 defining an opening 23 which forms a housing for a thermostatically actuated member as will hereinafter be more particularly described. Also extending from the lower portion of the casing 20, and being an integral part thereof, is a member 24 having a conduit or passageway 25 therein. The member 24 is threaded as indicated at 30 26 to connect the same to a gas burner indicated at 27 having an ordinary flame surface 28 and an air mixing vent 29 incorporated therein.

An off set portion of the casing 20 forms a 40 maintaining wall as indicated at 30 defining an opening 31, the conical tapering sides of which are adapted to receive and form a seat for the closure members or valves 32 and 33. A valve or closure 34 is centrally located in the end of the casing 20 adjacent the supply main, the tapering 45 wall of the casing forming a seat therefor as indicated at 35. A stem 36 of the valve 34 extends into a cylindrical opening in the casing 20 indicated at 37 and is threaded to a piston or guide member 38 as indicated at 39. The valve 34 is 50 normally maintained upon its seat 35 by the action of a spring 40 on the inner surface of the guide member 38. Obviously other and equivalent energizing means may be utilized without departing from the nature and spirit of the inven-

tion. A portion of the guide member 38 extends into a centrally located opening 41 in the casing 20 as indicated at 42. Adjacent and in alignment with the end of the extending guide member 42 is located a stem 43 extending through an opening in an inner wall 44 in the casing 20 and connected to a bellows member 45 situated in the opening 23. A cap member 46 is adapted to be firmly secured in position against the end portion of the circular wall 22. This connection may be made in any customary manner and is not indicated in the drawings. A tubular member 47 forming a portion of the cap 46 extends outwardly therefrom to a position substantially adjacent the flame surface 28 of the gas burner 27 and is adapted to contain an expansible fluid 47' by which the bellows member 45 is actuated. On account of the high temperature existing in the proximity of the flame it is desirable to utilize a number of cooling fins on the tubular member 47, one of which is indicated at 48. A tube 49 is adapted to be telescoped over the member 47 and maintained in any desired position thereon by a set screw 50. The tip of the tube 49 takes a position over the flame surface 28 and directly communicates the heat of the flame to the tubular member 47. In this manner the apparatus is made adjustable to fit various size burners and also provides an element easily replaced if destroyed by constant contact with the flame.

Referring more particularly to Fig. 3, the closures or valves 32 and 33 are located on a shaft or stem 51 and have the ordinary passageways 52 and 53 respectively incorporated therein. The valve 33 is rotatably connected through the shaft 51 to an operating or control block 54 having a lever or handle 55 extending therefrom. On the opposite side of the block 54 and extending from below the same is a pin 56 adapted to operate in a groove 57 located in the upper portion of the closure member 32, the end portions of the groove forming shoulders or stops as indicated at 58 and 59 adapted to coact with the pin 56 and determine the position of the valve 32 on the shaft 51. It is particularly desired to emphasize the fact that inasmuch as the valve 32 is loosely connected to the shaft 51 the movement of the same does not actuate the valve. The lower portion of the block 54 is constructed to define a circular opening 60 about the shaft 51 and an opening 61 making communication with the opening 41 at the center of the casing 20. A collar 62 is loosely mounted on the shaft 51 in the opening 60. Located on the collar 62 is an arm 63 having a tip 64 on the end thereof, the arm 63 extending through the openings 61 and 41 and placing the tip 64 in alignment between the stem 43 and the extending end of the piston member 42. A pin 65 is located on the valve 32 and is adapted to control the same by coacting with the movement of the arm 63 as will hereinafter be more particularly described.

A washer 66 and a screw 67 located in the extending portion of the shaft 51 firmly connects the block 54 on the same. The respective parts are maintained in their correct relative positions in the opening 31 by a collar 68 and screw 69. A conduit or passageway 70 in the casing 20 leads from the seat 35 of the valve 34 and is in alignment with one end of the passageway 53 located in the closure 33. The opposite end of the passageway 53 is in alignment with the passageway 25. It is obvious that as long as the valve remains on the seat 35 no gas will flow through the

valve 33. A conduit or passageway 71 directly connects the gas supply line 21' to one end of the closure passageway 52 when the valve 32 is turned on. The opposite end of the passage 52 is in alignment with a passageway 72 leading into the passageway 25. In this manner the closures 33 and 34 are by-passed by the passageways 71 and 72 controlled by the closure 32. Extending from the upper portion of the wall 30 are lugs 73 and 74, the inner surfaces of the same forming stops and determining the arc that the operating lever 55 may be moved through.

From the foregoing description the structure of the mechanism will be understood and its operation is as follows. In starting the mechanism the lever or handle 55 is turned to the on position against the lug 73 as clearly illustrated in Fig. 5. This simultaneously opens the main closure member 33 by placing the respective passageways 25, 53 and 70 in alignment and also by the action of the pin 56 on the shoulder or stop 59 opens the auxiliary closure member 32 thereby placing the respective passageways 72, 52 and 71 also in alignment. It is obvious that for a flow of gas through the main passageway the closure 34 must necessarily also be opened and consequently at this point the gas only flows from the main 21' through the passageway 71, valve 32 and passageway 72 and thence by way of passageway 25 to the burner 27. The gas is now ignited by the operator, the heat of the flame being transmitted to the expansible fluid 47' through the tip 49 and tubular member 47 causing the bellows member 45 to expand. The stem 43 of the bellows member 45 moves outwardly against the tip 64 and extending portion 42 of the piston or guide 38 thereby compressing the spring 40 and opening the valve 34 as clearly illustrated in Fig. 6. By the movement of the tip 64 the arm 63 is brought in contact with the pin 65 hereby changing the position of the valve 32 to close the same. Inasmuch as the closure 33 is already opened it is obvious that the flow of gas is simultaneously cut off from the auxiliary passageway and turned through the main passageway 70 to passageway 25 and thence to the burner 27. After the flow of gas has thus been established the height of the flame at the burner may be regulated by adjusting the valve 33, by means of the handle 55. It is readily apparent that in the event the gas flame be accidentally extinguished the cooling of the fluid 47' facilitates the contraction of the bellows member 45 whereby the valve 34 is returned to its seat 35 by the action of the spring 40 as illustrated in Fig. 7. In this manner the flow of gas through the main passageway 70 is terminated and inasmuch as the auxiliary passageway has heretofore been closed the flow of gas to the burner is shut off.

Referring to Figs. 8, 9 and 10 inclusive, a casing 75 is indicated at 75, one end of which is screw threaded as indicated at 76 to form a suitable connecting means to a gas supply main 76'. The opposite end comprises a circular wall 77 defining a cylindrical opening 78 which forms a housing 85 for a bellows member 79. The inner surface of the circular wall also serves as a guide for a piston member 80. Centrally located in the end of the casing 75, adjacent the supply main 76 is a closure member or valve 81 having a seat on the tapering sides of the casing as indicated at 82. A stem 83 of the valve or closure member 81 extends through a conduit or passageway 84 in the casing 75 and thence through a circular opening in a wall 85 and a packing member 86. The end of 75

the stem 83 is threaded as indicated at 87 and by this or equivalent means is firmly connected to an extending portion 88 of the piston member 80. By the action of a spring 89 on the end of the 5 extending portion of the piston 80 the closure member 81 is normally maintained on its seat 82. Closure members or valves 90 and 91 are so placed as to bring their respective openings 92 and 93 in alignment with a passageway 94 in the body 10 of the casing 75 when the said valves are turned on. One end of the passageway 94 in the casing 75 is directly exposed to the main gas supply line 76 as indicated at 95. The opposite end terminates in the lower portion of the casing 75 as 15 indicated at 96, the same being internally threaded to make a connection with an elbow 97. A central passageway 98 in the elbow 97 is directly in line with the terminating end of the passageway 94. The elbow 97 is threaded as indicated at 99 to connect the same to a gas burner 100. The gas burner 100 has an ordinary flame surface 101 and an air mixing vent 102 incorporated therein. The closure member 90 has a passage 103 extending from the opening 92 therein and adapted to make a connection with the passageway 84 when the same is turned on. The valves 90 and 91 are suitably controlled by operating levers 104 and 105 respectively. A holding washer 106 cooperates with a centrally located 20 set screw 107 fastened in the valve 90 to maintain the same firmly in position in the casing 75. The valve 91 is firmly maintained in the casing 75 by a plug 108, one end of which is screw threaded as indicated at 109 and adapted to position centrally in the valve. The plug has a collar 25 110, the inner surface of which maintains a holding washer 111 against the casing 75. At the opposite end of the plug 108 is a stem 112, on which one end of the spiral spring 113 is maintained. The opposite end of the spring 113 is connected to a pin 114 secured in the casing 75. The action of the spring 113 normally maintains the valve 91 in a closed position. A cap member 115 is secured by any well known means to the 30 end of the circular wall 77 and maintains a tubular member 116 so that the ends thereof are disposed to take a position substantially over the flame surface 101 of the burner 100. Cooling fins are indicated at 117. The tubular member 116 contains an expansible fluid 118 leading to the bellows member 79 as indicated at 119. In the operation of this mechanism the levers 104 and 105 are pressed together by the operator as 35 shown in Fig. 11. This establishes a flow of gas in the main 76 through the auxiliary passageway 94 and passages 92 and 93 and thence to the passageway 98 in the elbow 97 to the burner 100. The gas is now ignited and the heat therefrom expands the fluid 118 in the tubular member 116. 40 This in turn expands the bellows member 79 and thereby moves the piston 80 against the action of the spring 89 to move the closure 81 from its seat 82 as indicated in Fig. 12. In this type of mechanism it is necessary that the operator hold 45 the levers 104 and 105 together until the thermostatic bellow 79 opens the valve 80. This establishes the flow of gas through the main passageway 84 to valve 90 through passageways 94 and 98 and thence to the burner 100. 50 A single closure member 90 performs the functions of a double valve by connecting both the main and auxiliary passageways to the burner when in the on position. As soon as the flow of 55 gas through the mechanism has been established, as indicated in Fig. 12, the release of the hand of

the operator permits the closing of the valve 91 by the action of the spring 113. The height of the flame at the burner may now be adjusted by moving the lever 104 thus controlling the valve, 90, and placing the same in any desired position. It is now obvious that in the event that the flame be accidentally extinguished the contraction of the bellows member 79 will permit the spring 89 to return the valve 81 to its seat 82 thus preventing the flow of gas through the main passageway as 10 clearly illustrated in Fig. 13. Inasmuch as the auxiliary passageway has heretofore been closed it is obvious that the gas flow to the burner is completely shut off.

I claim as my invention:

1. In a fuel control mechanism for gas burners, a main fuel conduit, independently operated closures for said conduit, a conduit by-passing said closures, a closure for said last named conduit, means for simultaneously opening a closure for 20 each conduit, and thermal means for closing the closure for said by-pass conduit and simultaneously opening a closure in said first named conduit.

2. In a fuel control mechanism for gas burners, a main fuel conduit, independently operated closures for said conduit, a conduit by-passing said closures, a closure for said last named conduit, means for simultaneously opening a closure for each conduit, thermal means for closing the closure for said by-pass conduit and simultaneously 25 opening a closure in said first named conduit, and means tending to close said last named closure.

3. A device of the character described, a supply pipe, main and auxiliary conduits communicating therewith, means for simultaneously closing said conduits, means for simultaneously opening portions of said conduits, independent means for closing said main conduit, means responsive to temperature rise for closing said auxiliary conduit 40 and opening said main conduit, and means for closing said main conduit in response to temperature fall.

4. A safety fuel control device comprising a gas burner, a plurality of conduits for supplying fuel thereto, one of said conduits having a manually operable valve closable automatically, another of said conduits having an automatically closing valve and a manually operable valve, actuating means for simultaneously opening said 45 manual valves, and thermally responsive means for closing said first named valve and opening said last named valve.

5. A safety fuel control device comprising a gas burner, a plurality of conduits for supplying fuel thereto, one of said conduits having a manually operable valve closable automatically, another of said conduits having an automatically closing valve and a manually operable valve, actuating means for simultaneously opening said manual valves, and means for simultaneously opening said 50 automatic valve and closing said first named valve.

6. In a fuel control mechanism for gas burners, a main fuel passageway, independently operated valves for said passageway, a by-pass around said valves, a valve for said by-pass, means for simultaneously opening a valve of said passageway and the valve of said by-pass, thermal means for closing said by-pass and simultaneously opening another valve of said passageway, and means tending to close said last mentioned valve.

7. In a fuel control mechanism for gas burners, a main fuel passageway, independently operated valves for said passageway, a by-pass around said 75

valves, a valve for said by-pass, means including a common shaft for simultaneously opening a valve of said passageway and the valve of said by-pass, thermal means for closing said by-pass and simultaneously opening another valve of said passageway, and means tending to close said last mentioned valve.

8. A fuel control mechanism for hydro-carbon burners comprising in combination, a burner, a fuel supply main therefor, means for supplying fuel from said main to said burner, including two conduit portions, one of said portions having free communication with the fuel supply at the main, the other portion having a spring closed valve, a second valve for said other portion having a shaft fixed thereto, a valve for said first named portion loosely mounted on said shaft, manual means for simultaneously opening said last two valves, ther-

5 mally responsive means associated with said burner for opening said spring closed valve and closing said loosely mounted valve.

9. In a safety fuel cut off mechanism, the combination of a gas burner, a main supply pipe and two conduits establishing communication between said pipe and burner, three valves controlling said conduits, said valves being mounted for movement independently of one another, actuating means for simultaneously opening two of said valves, located in different conduits, one of the valves controlling communication directly with the supply pipe, energized means for normally closing said third valve, and thermally responsive means for simultaneously opening said third valve and closing the valve controlling direct communication with the supply pipe. 10 15

FRANK S. SUMMER.
